(57) **CLAIM**

The ornamental design for a ceramic heater, as shown and described.

DESCRIPTION

FIG. 1 is a front view of a ceramic heater showing our new design, the rear view, left side view and right side view being mirror images;

FIG. 2 is a top view thereof;

FIG. 3 is a bottom view thereof;

FIG. 4 is a cross sectional view taken along line 4-4 in FIG. 1, with the internal mechanism of the ceramic heater omitted for ease of illustration;

FIG. 5 is a cross sectional view taken along line 5-5 in FIG. 2, with the internal mechanism of the ceramic heater omitted for ease of illustration; and,

FIG. 6 is another front view thereof, shown with a different shaft in broken lines, the rear view, left side view and right side view being mirror images.

The drawings are lined for the color gray with long, horizontal dashed lines. The short, even dashed broken lines shown in the drawings represent portions of the ceramic heater that form no part of the claimed design.
